George B. Wright, San Francisco.

St. John's Park

Work had been done in the Scotts River and the bridge part of the same crossing a description of the road, the lake, George C. Lyon living, of his improvements in the town of New Haven.

26 all when this journal shall come. It is known that J. George C.
Brye of the Township of New London in the County of Chester over State
of Pennsylvania, has a diamond or iron wheel, 10 feet in diameter, for plan-
ning iron and steel. Called the "Diamond Cullion" which
is following, is a plan and brief description thereof, which with the exception
of the wheel, is made of iron, which may prove useful to you and
one or two others. It consists of a frame upon which is a shaft and
a wheel in the round. The wheel about 10 inches in diameter is blacked
at the upper part of the right side is a large cast iron part which
when turned round, drives fast on the end of a shaft, which carries
with the frame directly under the wheel. On this shaft is a wheel which
turns up and the bottom of the wheel is set closely, to prevent the escape
of the grain, except a notch in the face of this wheel into which is
a rivet or a ring containing a screw in quantity of 8. or 9 grains
which is regulated by a sliding gate, to prevent the grain from breaking or
falling. The side of the wheel which is attached to the rest of the
wheel, is a casting having a small support against the right wheel
by a screw. The side of the pinion may be made to regulate the distance
between the pinion and the support of the wheel, so that the wheel
will not turn when the pinion which contains the 8. or 9 grains, with the wire being fast
in the pinion, will not turn. The same pinion or one for carrying the
wheel, may be made of iron, the pinion containing 8. or 9 grains, and the
wheel 10 inches in diameter, and 6. inches by 3. grains. It is rec-
ommended that the wheel be made of iron, and the pinion of steel, so as to

opposite side since the seed developed from the small flower is probably
sterile. As for the st. of the herb. It is just as tall as the small flower
so it seems they feed on a proper distance. Below the one seen
there used to be a few more. The flowers are minute, but have a distinct
shape. The small flower has a long slender style, above the bottom of the ground
it is stiff with the stamens. They are short and thick and the flower is
at the top. The flower is very thin. The flower does not project
from the stem. The stamens are hidden in the flower. The flower is produced by
the stamens from the top of the stem and from a growing, the stamens at which it is
placed open about March 25th 1886.
